CLAIM

The ornamental design for a panel for phototypesetter or the like, as shown and described.

DESCRIPTION

FIG. 1 is a front perspective view of a panel for phototypesetter or the like showing our new design, the broken lines are for illustrative purposes only and form no part of the claimed design;

FIG. 2 is a top plan view thereof;

FIG. 3 is a front elevational view thereof;

FIG. 4 is a side elevational view thereof, the opposite side being a mirror image;

FIG. 5 is a rear elevational view thereof; and

FIG. 6 is a bottom plan view thereof.
